G. BYRON & C. SKIPWITH,
RAILWAY CAR STEP.
APPLICATION FILED NOV. 3, 1916.

1,211,078.

Patented Jan. 2, 1917.

UNITED STATES PATENT OFFICE.

GEORGE BYRON AND CLAUD SKIPWITH, OF WILLIAMS, ARIZONA.

RAILWAY-CAR STEP.

1,211,078.

Specification of Letters Patent.

Patented Jan. 2, 1917.

Application filed November 3, 1916. Serial No. 129,356.

To all whom it may concern:

Be it known that we, GEORGE BYRON and CLAUD SKIPWITH, citizens of the United States, residing at Williams, in the county of Coconino and State of Arizona, have invented certain new and useful Improvements in Railway-Car Steps, of which the following is a specification.

The present invention relates to railway rolling stock and has particular reference to new and useful improvements in extensible car steps, the device having for its primary object the provision of a novel and improved type of extensible car step for application to the standard step of railway cars to assist passengers in boarding and leaving a car.

Another object of our invention is to provide an extension section for application to the standard railway car step without materially altering the structure of the same so as to obviate the use of the stool now usually employed.

Our invention also contemplates the provision of novel means for raising and lowering the extension step section so that when not in use a full clearance is allowed for the car, no projecting parts being present which might strike objects adjacent a railway track.

A still further object of our invention is to provide a step section of the class described which is simple in construction, strong and durable, is capable of universal application and may be quickly and easily installed.

Other objects and advantages to be derived from the use of our improved extensible railway car step will appear from the following detailed description and the claims, taken with an inspection of the accompanying drawing, in which:

Figure 1 is a fragmental side elevational view of one end of a railway car showing an extension step embodying the improvements of our invention; and Fig. 2 is a fragmental end view of the same.

Referring more particularly to the drawing, wherein similar characters of reference designate like and corresponding parts throughout the various views, 10 designates the side portion of a railway car having a platform 11 extending from the end thereof. Our improved step is to be applied to the standard car step, one arrangement of the standard step being shown.

The fixed step section is designated S and

consists of a plurality of steps 12 supported by the side portions 13 and 14 connected at 15 to the platform 11 of the car.

The extensible step section of our invention is designated S' and consists of a plurality of steps 16 carried by side portions 17 and 18. The side portions 17 and 18 are pivotally mounted as at 19 on the inner faces of the side members 13 and 14, respectively, so that said section S' may be folded upwardly into the section S as indicated in dotted lines in Fig. 2.

We provide means for raising and lowering the step section S' from the platform of the car, said means including a link 20, the upper end of which is laterally bent as at 21 and pivotally connected at 22 to one of the hinge members 19. The lower end of the link 20 is pivotally connected at 23 to a bracket 24 carried by the side portion 17 of the step section S'. A manipulating rod 25 is provided, said rod being formed with an enlarged lower end bent laterally and pivotally connected at 26 to the intermediate portion of the link 20. The rod 25 passes through the platform 11 and is formed with a curved portion 27, the upper end of the rod terminating in a handle 28.

In use it will be noted that the extensible section S' may be moved to the outer position for use by depressing the rod 25. By moving the rod upwardly the step may be returned to folded or closed position. If desired the step section S' may be maintained in the folded position by means of the usual trap door employed on vestibuled railway coaches. It will be readily apparent that the device of our invention may be easily applied to any of the existing standard types of car steps without materially altering the structure of the same.

From the above description taken in connection with the accompanying drawing, it is thought that a clear and comprehensive understanding of the construction, operation and advantages of our invention may be had, and while we have shown and described the device as embodying a specific structure, we desire that it be understood that such changes may be made in said structure as do not depart from the spirit and scope of the invention as claimed.

Having thus fully described our invention, what we claim as new and desire to secure by Letters Patent, is:

1. In a device of the character described,

the combination with a fixed step section, of a movable step section hingedly connected to the bottom of first said section and receivable within the same when not in use, a link fixedly connected to said movable step section and pivotally connected to the first said section, and an operating rod extending to the top of first said step section and pivotally connected with the intermediate portion 5 of said link to raise and lower second said step section.

2. A device as specified, including the combination with a fixed step section, of a movable step section pivotally connected to the

lower end of first said section and receivable 15 within the same when not in use, a link pivotally connected with first said section and fixedly connected with second said section, and an operating rod slidable along first said section and pivotally connected with the intermediate portion of said link to raise and lower second said step section to bring the same into and out of operative position. 20

In testimony whereof, we affix our signatures hereto.

GEORGE BYRON.
CLAUD SKIPWITH.
